Primary Examiner — Phillip S Hyder(74) *Attorney, Agent, or Firm* — Fox Rothschild LLP(57) **CLAIM**

The ornamental design for a wire bonding wedge tool, as shown and described.

DESCRIPTION

FIG. 1 depicts a perspective view of a wire bonding wedge tool.

FIG. 2 depicts a second perspective view of the wire bonding wedge tool of FIG. 1, wherein FIG. 2 is rotated axially 90 degrees relative to FIG. 1.

FIG. 3 depicts a front side elevation view of the wire bonding wedge tool of FIG. 1.

FIG. 4 depicts a right side elevation view of the wire bonding wedge tool of FIG. 1.

FIG. 5 depicts a left side elevation view of the wire bonding wedge tool of FIG. 1.

FIG. 6 depicts a rear side elevation view of the wire bonding wedge tool of FIG. 1.

FIG. 7 depicts a top plan view of the wire bonding wedge tool of FIG. 6; and,

FIG. 8 depicts a bottom plan view of the wire bonding wedge tool of FIG. 6.

The broken lines in the figures depict portions of the wire bonding wedge tool that form no part of the claimed design.

1 Claim, 5 Drawing Sheets(56)
